UNITED STATES PATENT OFFICE.

BERNE NADALL, OF KINGSTON-UPON-THAMES, ENGLAND, ASSIGNOR TO
THE LINOTYPE COMPANY, LIMITED, OF LONDON, ENGLAND.

DESIGN FOR A FONT OF TYPE.

SPECIFICATION forming part of Design No. 35,319, dated November 26, 1901.

Application filed May 17, 1901. Serial No. 60,775. Term of patent 14 years.

To all whom it may concern:

Be it known that I, BERNE NADALL, a citizen of the United States of America, residing at Kingston-upon-Thames, in the county of Surrey England, have invented and produced a new and original Design for a Font of Type, of which the following is a specification.

My new and original design for a font of printing-type is illustrated in the accompanying drawing, the upper-case letters, characters, numerals, and punctuation-marks being shown on one sheet and the lower-case letters on a second sheet.

A characteristic feature of the upper-case letters is that the serifs of the letters which include straight lines in their formation are so connected with said lines as to form substantially triangular-shaped feet or heads therefor. This is particularly noticeable in the letters A, E, F, H, I, K, L, M, N, P, R, and T.

The right-hand inclined line of the letter A is heavier than the left-hand inclined line, and the upper end of said heavier line is inclined to the horizontal, and also the lighter left-hand-inclined line. Both ends of the curved line forming the letter C terminate in similarly-formed triangular enlargement.

The intermediate horizontal line of the letter E is considerably shorter than the upper and lower lines thereof and terminates in a head the face of which is inclined to the perpendicular and extends more below than above said horizontal line. The lower horizontal line of the letter F is similar in form to the said middle line of the letter E.

The outer faces of the terminals of the horizontal lines of the letters E, F, L, and Z and of the curves in the letters C, G, and S are also inclined to the perpendicular.

The curved line forming the letter G has at its upper end a terminal like that found on the ends of the curve in the letter C, and the vertical line in which the lower end of said curved line terminates is relatively short and is wider or thicker than the adjacent curved line, so that an indentation or recess is formed in the lower edge of said letter where said lines join. The vertical lines of the letters H, I, J, K, and L have at both their upper

and lower ends the characteristic triangular formation before referred to, and the letter J is also of greater length than the other letters, extending somewhat below the plane upon which the others may be considered as resting.

In forming the letters M and N the heavy inclined lines are carried slightly beyond the left-hand vertical or perpendicular lines and cut off on a horizontal line, thus forming a substantially triangular head at the upper end of each of said perpendiculars. The letters O and Q are slightly oval or elliptical, the lines forming them being somewhat thinner at the top and bottom than at the sides. The tail of the Q is relatively short and extends substantially perpendicular.

Both members of the letters S are of the same form, the terminals thereof lying in the same vertical of the outermost portions of the curves.

The interior heavy line of the letter W is carried somewhat beyond the upper end of the lighter line to the left and is expanded slightly to the right at its upper end to form a triangular-shaped head.

It will be noticed also that in the diphthongs the letter E has the characteristic features above pointed out.

The lower-case letters likewise present the prominent characteristic of having substantially triangular-shaped feet or terminals for most of the perpendicular lines employed in forming the letters and in having the upper end of the stems or vertical lines inclined to the horizontal. In forming such combinations as fh, fi, ff, ft, &c., the horizontal line of the f is placed only on the left-hand side of the perpendicular.

Having thus described my invention, what I claim, and desire to secure by Letters Patent, is—

The design for a font of printing-type, substantially as shown and described.

In testimony whereof I affix my signature in presence of two witnesses.

BERNE NADALL.
